UNITED STATES PATENT OFFICE.

JOHANNES KRONE, OF ESSEN, GERMANY, ASSIGNOR TO FRIED. KRUPP, OF SAME PLACE.

FLUID-BRAKE FOR GUNS.

SPECIFICATION forming part of Letters Patent No. 635,557, dated October 24, 1899.

Application filed February 21, 1899. Serial No. 708,319. (No model.)

To all whom it may concern:

Be it known that I, JOHANNES KRONE, a citizen of the German Empire, residing at Essen, Germany, have invented certain new and useful Improvements in Fluid-Brakes for Guns, of which the following is a specification.

My invention has reference to improvements in fluid-brakes for guns of the class provided with separate accumulators. In such apparatus the accumulator is usually connected by pipes with the recoil brake-cylinder or cylinders, said pipes being provided with valves for regulating the running-out movement of the gun-barrel. This arrangement not only requires considerable space, but, owing to the many connections requiring packing, it cannot very well be kept tight. Besides, many important parts are unprotected, and consequently the apparatus is in danger of being injured by pieces of exploding shells.

The object of the present invention is to remedy these defects and to construct a fluid-brake extremely compact, without pipes or conduits, with but few parts requiring packing, adapted to be readily taken apart, and secured against pieces of exploding shells.

To this end my invention consists, essentially, in arranging a separate running-out brake-cylinder in line with and in communication with the liquid-space of the accumulator.

The nature of my invention will best be understood when described in connection with the accompanying drawings, in which—

Figure 1 represents a vertical longitudinal section of one of the recoil brake-cylinders. Fig. 2 is a horizontal section of the whole fluid-brake. Fig. 3 is a cross-section on the line 3 3, Fig. 2. Fig. 4 illustrates a modification of the running-out brake. Figs. 5 and 6 illustrate other modifications.

Similar letters of reference designate corresponding parts throughout the several views of the drawings.

Referring now to Figs. 1 to 3 of the drawings, the letter B designates the gun-barrel; D, the two recoil brake-cylinders; H, the accumulator or running-out cylinder, the recoil brake-cylinders and the accumulator being connect-

ed to or forming part of the cradle within which the gun-barrel slides back and forth.

c^2 c^2 are channels connecting the liquid-spaces of the accumulator H and the recoil brake-cylinders D. Each of the recoil-brakes 55 consists of a recoil brake-cylinder D, a differential piston C C', and a brake-shank F. The differential piston is formed of a hollow plunger C, secured to the horn A of the gun-barrel B and of the piston proper, C'. Communication between the two sides of the piston C is established by channels c^2 c^2 and by the bore c of the differential piston C C'.

F is the outer cylinder-head, which carries the central conical brake-shank F, which latter projects into the bore c of the piston C C'. All the hollow spaces in the brake-cylinders D and in the brake-pistons C C' are filled with a suitable liquid, such as water or oil.

J is a piston within the accumulator-cylinder. The space K to the right of the piston within said accumulator-cylinder is filled with compressed air, which tends to force the piston toward the head P of said accumulator.

The piston J is connected to or forms part of 75 a cylinder with a bore O, opening toward the head P and forming the cylinder of the running-out brake. The head P of the accumulator receives the running-out brake-piston L. The space N at the right-hand end of the cy- 80 lindrical bore O is in communication with the space at the left-hand end through channels n n, extending through the brake-piston L. These channels n n are closed by means of a

spring-valve M, which opens toward the space 85 N, but which does not completely close the channels, in view of very small channels e extending through said valve. From the piston J a cylindrical rod i projects and passes through the piston L, which said rod is fitted 90 so as to be tight under the pressure of the liquid. This rod simply serves as a means for watching the motion of the running-out piston J.

The operation of the apparatus is as follows: 95 During the recoil of the gun-barrel in the direction of the arrow in Fig. 1 the differential hollow pistons C C' C C' are forced into the cylinders D D and over the conical shanks F F, thereby causing the liquid to pass from 100

one side of the pistons C', through the annular spaces E, between the shanks F and the walls of the bore c, and through the channels c' to the other side of the pistons C'. The liquid being throttled in its passage through the narrow annular spaces E, energy is required to force the liquid through such spaces, and this energy is supplied by the gun which loses potential energy, or, in other words, is braked. Owing to the conical shape of the brake-shank F, the resistance to the passage of liquid or the back pressure on the pistons C' is gradually increased. Since at the same time the total volume of the hollow spaces within the brake-cylinders and the hollow pistons C C' is gradually decreased, liquid is forced into the accumulator II, with the result of producing an inward movement of the running-out piston J, and consequently a further compression of the compressed air contained in the gas-space K, so that energy is stored up. As the liquid forces the accumulator-piston J inwardly it enters the bore O, passes through the channels n, opens the valve M, and passes into the space N at the right-hand end of the bore O. When the recoil is completed by the exhaustion of the potential energy of the gun, partly in frictional work and partly by compressing gas in the accumulator, the compressed gas or air in the space K of the accumulator II forces the accumulator-piston J toward the head P of the accumulator-cylinder. The liquid in the accumulator flows back into the cylinders D, forcing the pistons C' C' outwardly—that is, in a direction opposite to that indicated by the arrow in Fig. 1, so as to run the gun back into battery. At the instant when the recoil is completed the valve M closes, so that during the running-out movement the liquid must pass through the narrow openings e from the space N to the channels n and to the recoil-cylinders D. By these narrow openings the flow is throttled and the too-rapid running-out movement checked—that is, the arrangement acts as a running-out brake. The small openings e may also be omitted, if desired. Fig. 4 shows this construction, wherein the piston L is loosely fitted to the cylindrical bore O, or instead of so loosely fitting the piston the bore O may be slightly tapered, for instance by making it larger in diameter at b' than at b. By these means in running out—that is, when the liquid is forced from the space N to the bore O of the running-out cylinder—the liquid first has a comparatively free passage, while the opening is gradually reduced.

Figs. 5 and 6 show modifications in which the running-out brake-piston L is not sta-

tionary, but is movable within a cylinder O'. The piston L' is rigidly connected to the air-compressor or accumulator-piston J'. In the modification shown in Fig. 5 the valve M' has small channels e', while in Fig. 6 these channels are omitted and the piston L' is loosely fitted within the cylinder O'. The operation of these modifications is the same as described with reference to Figs. 1 to 4.

The principal parts of the running-out brake in both of the modifications consist of a cylinder with the bore O and a piston L, one of which parts is rigidly connected with the accumulator-cylinder, and thereby to the cradle, while the other part is connected to the piston of the accumulator-cylinder.

What I claim as new is—

1. In a liquid recoil-brake for guns, the combination with one or more recoil brake-cylinders D, the accumulator-cylinder II and the accumulator-piston J, of a separate running-out brake-cylinder and a piston therein, one of these parts being rigidly connected to the accumulator-cylinder, the other part being connected to the accumulator-piston; a valve opening under the recoil pressure of the liquid and freely admitting liquid into the space between the closed end of the running-out brake-cylinder and its piston; and a contracted opening or openings for the passage of the liquid in opposite direction between the two sides of the running-out brake-piston, substantially as and for the purpose specified.

2. In a liquid recoil-brake for guns, the combination with one or more recoil brake-cylinders D, the accumulator-cylinder II and the accumulator-piston J, of a separate running-out brake-cylinder with the bore O and a piston L therein, said running-out brake-cylinder being rigidly connected or forming part of the accumulator-piston J while the running-out brake-piston L is rigidly connected with the accumulator-cylinder head P; a valve M in said running-out brake-piston L opening under the recoil pressure of the liquid and freely admitting liquid into the space between the closed end of the running-out brake-cylinder and its piston; and a contracted opening or openings for the passage of the liquid in the opposite direction between the two sides of the running-out brake-piston, substantially as and for the purpose specified.

In testimony whereof I have hereunto set my hand in the presence of two subscribing witnesses.

JOHANNES KRONE.
